(57) **CLAIM**

The ornamental design for a mosquito-repellent lamp, as shown and described.

DESCRIPTION

FIG. 1 is a top perspective view of a mosquito-repellent lamp showing my new design;

FIG. 2 is front elevational view of thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a bottom perspective view thereof;

FIG. 9 is a top perspective view thereof in an alternate position of use; and,

FIG. 10 a perspective view thereof in an alternate position of use.

The broken lines depict portions of the mosquito-repellent lamp in which the design is embodied that form no part of the claimed design.
